UNITED STATES PATENT OFFICE

2,127,671

MEANS FOR PROTECTING THE SIDES OF
CRAFT

Carl Alexander Baumann, Jr., Clairton, Pa.

Application November 13, 1936, Serial No. 110,761

3 Claims. (Cl. 114—219)

This invention relates particularly to a method of attaching protective material to the sides of a plurality of craft so that only the protective material contacts when any of the craft are adjacent each other.

The sides of craft are ordinarily protected by securing strips of protective material horizontally thereto. Then when two craft are placed side by side, the strips of protective material often do not meet for various reasons, such as, for example, one craft having a different draft than the other, or one craft being at a slight angle to the other. The protective strips would then rub on the sides of the craft and wear them away in places, thereby functioning in exactly an opposite manner from that desired. Furthermore, another disadvantage of the old method of securing protective material to craft is that the sides of the strips have been known to engage and hold the craft together.

One object of this invention is to overcome the above and other disadvantages of known methods of protecting the sides of craft, and to provide protective means that will prevent the sides of adjacent craft from coming into contact with the protecting material on the other craft.

The above and further object will become apparent by referring to the following description and the accompanying drawing, in which:

30 Figure 1 is an elevation of a barge that is provided with one embodiment of my method of protecting the sides of craft, the protective material on the rear side of the barge being indicated by dotted lines; and

35 Figure 2 is an end elevation of Figure 1.

Referring more particularly to the drawing, the numeral 2 indicates generally a barge. My novel method of protecting the sides of craft is adapted to be used with all types and the barge 2 is shown merely as a specific example of a craft whose sides can be protected thereby. The barge 2 has substantially vertical parallel sides 4 and 6 and ends 8 and 10. For convenience, the sides 4 and 6 may be called the starboard and port sides, respectively, and the ends 8 and 10 the bow and stern, respectively. The starboard side 4 and the port side 6 are protected by diagonally arranged rubbers, bumpers or strips 12 and 14 which are secured or attached thereto. The strips 12 and 14 are made from any suitable protective material, such as steel, rubber or rope depending upon the characteristics desired of them. The strips 12 preferably are parallel and slant upwardly toward the bow 8 and the strips 14 may be parallel and slant upwardly toward the stern 10. How-

ever, the strips 12 must slant in a different direction from the strips 14 and preferably the strips 12 and 14 make the same angle with the horizontal, as shown in the drawing.

To correctly space the strips 12 and 14, they should be so arranged that if the strips on one side of the craft were projected to the other side of the craft, the projection would intersect the strips on such side.

As the strips 12 and 14 are placed on the barge 2 to protect the sides thereof when placed against another barge or craft, the strips 12 and 14 must project from the outside surfaces of the sides and be so positioned that they will always contact with the strips placed on other craft. To achieve this result, the strips placed on the craft must be uniformly positioned. As all craft have corresponding sides, such as starboard and port, or right and left, the strips on the starboard or right side can uniformly be made to slope in one direction and the strips on the port or left side can uniformly be made to slope in the opposite direction. After placing the strips on the craft in this manner, the strips on adjacent sides of adjacent craft will always contact as they are slanted in different directions. The strips are so spaced and of such length that it is not possible for a strip to bear upon the side of an adjacent craft as the strip is of such length that it must contact at least one strip carried by the other craft.

Although I have shown the strips 12 and 14 on only the sides 4 and 6 of the barge 2, protective strips could be placed on the ends 8 and 10, if desired, in accordance with the teachings of my invention.

While I have shown and described a specific embodiment of my invention, it will be understood that I do not wish to be limited exactly thereto, since various modifications may be made without departing from the scope of the invention as defined by the following claims.

I claim:

1. A craft having a series of elongated strips of protecting material projecting from its sides and arranged at an angle to the horizontal, the strips 45 on one side being of such length and at such an angle as to intersect the projections of the strips from the other side so that when two or more of such craft having similarly positioned strips thereon are positioned alongside each other the 50 strips of protecting material will necessarily contact with each other.

2. A barge or similar craft having vertical sides, a plurality of outwardly projecting protective strips arranged diagonally and in substantially 55

parallel relation on the outside surface of one of said sides and a plurality of like outwardly projecting protective strips arranged diagonally opposite and in substantially parallel relation on the outside surface of the opposite side.

5. 3. A barge or similar craft having vertical sides, a number of outwardly projecting protective

members arranged diagonally and in parallel relation on the outside surface of one of said sides and a similar number of outwardly projecting protective members arranged diagonally opposite and in parallel relation on the outside surface of the opposite side.

5. CARL ALEXANDER BAUMANN, Jr.
